(57) CLAIM

The ornamental design for a bread box, as shown and described.

DESCRIPTION

FIG. 1 is a perspective view of a bread box showing our new design;

FIG. 2 is a perspective view thereof in an open configuration;

FIG. 3 is a front elevation view of FIG. 1;

FIG. 4 is a rear elevation view thereof;

FIG. 5 is a top plan view thereof;

FIG. 6 is a left elevation view thereof; and,

FIG. 7 is a right elevation view thereof.

The broken lines in the drawings depict portions of the bread box that form no part of the claimed design.

1 Claim, 7 Drawing Sheets
